BLOWPIPE IGNITING APPARATUS

Lloyd W. Young, Elizabeth, N. J., assignor, by
mesne assignments, to Union Carbide and Car-
bon Corporation, a corporation of New York

Application October 19, 1934, Serial No. 749,051

12 Claims. (Cl. 200—53)

This invention relates to blowpipe igniting apparatus, and more particularly electric apparatus for lighting blowpipes.

In the operation of blowpipes it is not always economical or convenient to employ a hand lighter or a constantly burning pilot flame for lighting the operating jet. Ignition is therefore effected at times by means of an electric spark between two terminals, of which the blowpipe tip 10 may be made one and the work piece the other. With such an arrangement it has been found that if the operator allows contact to be made between the terminals for any appreciable period of time, as by laying the blowpipe down upon the work, 15 the short circuit thus produced may damage the source of electromotive force which is used. Thus, a transformer may be overheated or a battery discharged. It has accordingly been found desirable to complete the electric circuit through 20 the blowpipe tip only for a short interval of time during which ignition is to be effected, and to break the circuit at other times. It is also highly desirable that the circuit should be completed automatically and as an incident to the opening 25 of the gas valves that control the jet emitted by the blowpipe.

One object of the invention therefore, is to provide a blowpipe igniting apparatus wherein the circuit is closed only when needed for ignition. Another object is to provide such an apparatus in which the circuit will be broken at all times when not needed for ignition. A further object is the construction of such an apparatus in a form which will permit automatic closing of the 35 circuit while the gas valve is being opened. Other objects will be apparent from the following specification.

The invention is shown by way of illustration in the accompanying drawing, in which:

40 Fig. 1 is a side elevation of a blowpipe embodying the invention, the electric circuit and a work piece being shown in semi-diagrammatic form;

Fig. 2 is an enlarged fragmental section taken longitudinally of the blowpipe, showing the im- 45 proved igniting apparatus and gas valve control lever;

Fig. 3 is a section on the line III—III of Fig. 2;

Fig. 4 is a longitudinal mid-section through the switch illustrated in Fig. 3;

50 Fig. 5 is a broken elevation similar to that shown in Fig. 1, illustrating a variant form; and

Fig. 6 is a similar elevation illustrating another variant form.

According to the present invention, the blow- 55 pipe is equipped with a gas control lever piv-

oted thereto, which lever carries a push switch having one side thereof electrically connected to the blowpipe and the other side thereof connected to a conductor insulated from the blowpipe. Operation of the gas control lever automatically operates the push switch. A second lever may be pivoted to the gas control lever in such a way that motion of the gas control lever will cause the second lever to operate the push switch and to pass out of contact with the switch almost im- 10 mediately.

Referring now to the drawing, it will be seen that they show a blowpipe 10, comprising a handle 11, a stem 12, and a tip 13, and having the usual valve block 14 attached to the rear of 15 the handle. The blowpipe may be either a cutting or deseaming blowpipe as illustrated in Fig. 1, or a welding blowpipe as illustrated in Figs. 2 and 6. It will be obvious that the invention is applicable to blowpipes generally. Adjustable 20 shut-off valves 15 and 16 control the flow of oxygen and fuel gas to the blowpipe. A button B for controlling the cutting oxygen valve is shown in the cutting or deseaming blowpipe illustrated in Fig. 1. 25

The valve block 14 contains a valve assembly for controlling the rate of gas flow through the blowpipe. This valve assembly need not be described except to state that the valve or valves thereof are spring-closed and are opened by a 30 pull exerted upon their valve stems 17, and may be similar to those more fully disclosed in Patent No. 2,095,710 which issued on October 12, 1937, to J. W. Offutt and W. B. Hampton. A gas control lever 18 is pivoted as at 19 to the blowpipe 10. 35 and a grip-shaft 20 thereof extends longitudinally of the blowpipe. An end 21 of the gas control lever 18 extends on the opposite side of the pivot 19 from the grip-shaft 20 and engages the valve stems 17. It will be understood therefore, that 40 if the operator grasps the handle 11 of the blowpipe 10 and closes his hand about the grip-shaft 20 of the lever 18, the resulting movement of the lever about the pivot 19 will cause the end 21 of the lever to pull the valve stems 17 outwardly of 45 the valve block 14, opening the valves forming the valve assembly contained therein. Release of the grip-shaft will permit the valves to close by reason of the spring action exerted within the valve block 14. The valves in the valve block 14 are 50 "gas saver" valves, and are always opened fully when the grip-shaft 20 of the gas control lever 18 is lifted. The valves 15 and 16 are set to control the oxygen and fuel-gas flow through the blowpipe. Thus, the proportions of oxygen and 55

fuel-gas required for a proper welding or heating flame are determined by the setting of the valves 15 and 16.

Ignition of the gases issuing from the tip 13 of the blowpipe is caused by an electric spark between the tip and the work piece 22 upon which the blowpipe operates. An electric circuit through the blowpipe and the work piece serves to produce the spark. In the embodiment here illustrated, a conductor 23 connects the work piece with a source of electromotive force, here shown as a battery 24, and a second conductor 25 connects the battery with the lever 18. The conductor 25 is, of course, insulated from the blowpipe and the control lever.

Means is provided for closing the circuit only when ignition of the gases is required, and for breaking the circuit when the blowpipe is not in operation or after the blowpipe has been ignited.

To this end the lever 18 carries a push switch which is normally open, which is closed as the lever is operated to open the gas control valve or valves, and which is opened again when the valves are opened or closed. Thus, the push switch is closed and opened again with each complete movement of the lever 18. One side of the push switch is electrically connected to the blowpipe and the other side to the conductor 25.

In the embodiment illustrated in Figs. 1, 2 and 3, a push switch 26 is carried by the control lever 18. The push switch 26 is enclosed in two bushings (see Fig. 4), one a metal bushing 27 which is fitted in an opening 28 in the lever, extending inwardly thereof. The metal bushing is welded, soldered or otherwise attached to the lever by means of an external end flange 29. The metal bushing 27 is internally threaded to receive an externally threaded end 30 of a second bushing 31 of insulating material.

The bushing 31 of insulating material has an axial bore therethrough which is internally threaded, and a stationary contact member 32 is carried by an adjustable screw member 33 which may be turned to advance or retract the stationary contact member 32 within the bushing 31. The insulated conductor 25 enters the bushing 31 substantially at right angles to the axial bore therein, and a clamping screw 34 secures the bare end of the conductor against the head of the adjustable screw 33, thus, completing the electric circuit from the battery 24 to the stationary contact member 32.

From the foregoing it will be evident that the stationary contact member 32 is completely insulated from the metal bushing 27 and from the control lever 18, and also that the position of the stationary contact member may be adjusted axially of the bushing 31. Obviously the details of this construction may be varied to secure the same result.

The metal bushing 27 has an axial opening 35 therein at the end opposite the external flange 29. A plunger 36 is disposed in the metal bushing 27 and has a rounded end 37 projecting through the opening 35. An annular flange 38 is formed on the plunger 36 surrounding the rounded end 37 and bearing upon the internal face of the bushing 27 surrounding the opening 35, thereby preventing the plunger from moving out of the bushing. The plunger 36 also has a hollow shaft 39, in axial alignment with the rounded end 37 and the annular flange 38, extending away from the rounded end and toward the stationary contact member 32. The open end of the hollow shaft 39 is spun or otherwise

turned inwardly for a purpose which will become apparent.

A helical spring 40 is disposed within the metal bushing 27 between the inner face of the annular flange 38 and the inner end of the externally threaded end 30 of the bushing 31, thereby holding the plunger 36 yieldably in position with its rounded end projecting through the axial opening 35 and beyond its end. A movable contact member 41 is carried by the plunger 36 and has a contact point 42 which extends through the opening in the hollow shaft 39 about which the end thereof is spun. The movable contact member 41 is enlarged beyond the contact point 42 so that it normally bears upon the inner face of the spun end of the hollow shaft 39, and a shank 43 extends axially through the hollow shaft 39 toward the rounded end 37, fitting slidably into a cylindrical recess therein. A helical spring 44 surrounds the shank 43 and tends to maintain the movable contact member in extended position with the contact point 42 as far from the rounded end 37 as is possible.

Thus, pressure upon the rounded end 37 is yieldably opposed by the action of the helical spring 40 and pressure upon the movable contact point 42 is yieldably opposed by the helical spring 44.

It will be appreciated, also that the movable contact is in electrical circuit when the lever 18 is operated, in the embodiment illustrated in Figs. 1, 2 and 3, by means of a second lever 45 pivoted as at 46 to the lever 18 and having an arm 47 thereof in contact with the blowpipe. The other arm 48 of the second lever 45 extends adjacent the rounded end 37 of the movable contact assembly and has a roller 49 journaled thereon for rolling contact with the rounded end 37. A spring 50 bent around the pivot 46 of the second lever 45 has one end in contact with the arm 47 of the second lever and the other end in contact with the first named lever 18, and operates to maintain the arm 47 against the blowpipe and the arm 48 carrying the roller 49 away from the rounded end 37. When the grip-shaft 20 of the lever 18 is drawn toward the blowpipe handle, the end 47 of the second lever 45 is moved toward the grip-shaft, thereby moving the arm 48 past the rounded end 37 of the push switch 26. This causes the roller 49 to roll over the rounded end 37, depressing the movable contact assembly and causing electrical connection between the movable contact 42 and the stationary contact 32. As the roller 49 passes beyond the rounded end 37, the helical spring 40 returns the movable contact assembly to its original position thereby breaking the electrical connection. The helical spring 44 provides flexibility between the rounded end 37 and the movable contact point 42, so that the contacts may always make perfect electrical connection, yet no lateral strain need ever result to the second lever 45 or its pivot 46 as the roller 49 passes over the rounded end 37.

If, therefore, the blowpipe tip 13 is rubbed along the work piece 22, the lever 18 is operated, and the gases are caused to issue from the tip, the electrical contact caused by movement of the lever 18 will cause a spark between the blowpipe tip 13 and the work piece, which will light the gases. This spark will exist only momen-

5 tarily because of the short period of contact as already described, and damage to the source of electromotive force or unnecessary use of current will be avoided. As the grip-shaft 20 is released and the blowpipe gases are shut off, contact is again made in the push switch but this is of no importance since there is no gas flowing through the blowpipe to be ignited.

10 In the embodiment illustrated in Fig. 5, no second lever is employed but a simple push switch 26a is attached to the lever 18, and makes contact with the blowpipe when the valve or valves opened. A leaf spring arrangement, or brush, in the push switch 26a causes contact to be broken 15 when the plunger is fully depressed (in well-known manner), so the flow of current through the blowpipe is disrupted when the valves are fully open.

15 In the apparatus shown in Fig. 6, the push switch is mounted on the blowpipe handle 11, instead of on the lever 18, but otherwise the operation is the same.

20 The examples here illustrated and described are presented merely to indicate how the invention may be applied. Other constructions following the principles of the invention but differing in detail from the forms here described will readily suggest themselves to those skilled in the art.

25 I claim:

30 1. A blowpipe igniting apparatus comprising a lever pivoted to the blowpipe, a push switch carried by said lever and an electric conductor insulated from the blowpipe, said switch having one side thereof electrically connected to the blowpipe and the other side thereof connected to said conductor.

35 2. A blowpipe igniting apparatus comprising a gas control lever pivoted to the blowpipe, a push switch carried by said lever and operable by movement of said lever, and a conductor insulated from the blowpipe, said push switch having one side thereof electrically connected to the blowpipe and the other side thereof connected 40 to said conductor.

45 3. A blowpipe igniting apparatus comprising a gas control lever pivoted to the blowpipe, a movable electric contact member carried by said lever, and a second lever for actuating said member, said second lever being pivoted to said first named lever.

50 4. A blowpipe igniting apparatus comprising a gas control lever pivoted to the blowpipe, a movable electric contact member carried by said lever, and a second lever for actuating said member, said second lever being pivoted to and actuated by said first named lever, and having an arm thereof in contact with the blowpipe.

55 5. A blowpipe igniting apparatus comprising a gas control lever pivoted to the blowpipe, a movable electric contact member carried by said lever, said member having a rounded projecting end, and a second lever pivoted to said first named lever, said second lever having one arm 60 thereof in contact with the blowpipe, the other

5 arm of said second lever being disposed adjacent the rounded end of said contact member and having a roller journaled thereon for rolling contact with the rounded end of said member for actuating the same.

6. A blowpipe igniting apparatus comprising a gas control lever pivoted to the blowpipe, a movable electric contact member carried by said lever, said member having a rounded projecting end, a spring holding said member away from its 10 coating contact point, a second lever pivoted to said first-named lever, and a spring acting against said first-named lever and one arm of said second lever to hold said second lever in inoperative position, said second lever having one 15 arm thereof in contact with the blowpipe, the other arm of said second lever being disposed adjacent the rounded end of said contact member and having a roller journaled thereon for rolling contact with the rounded end of said member for actuating the same.

7. An igniting circuit comprising a blowpipe having a handle, a valve operating lever and a push switch for closing said circuit, both carried by the handle, in combination with a second 25 lever pivoted to said first-named lever and disposed in operative relation to said push switch for operating the same.

8. An igniting circuit comprising a blowpipe having a handle, a valve operating lever pivoted 30 to the handle, and a push switch for closing said circuit also carried by the handle, in combination with a second lever pivoted to said first-named lever and disposed in operative relation to said push switch for operating the same. 35

9. An igniting circuit comprising a blowpipe having a handle, a valve operating lever pivoted to the handle, and a push switch for closing said circuit carried by said lever, in combination with a second lever for operating said push switch, 40 said second lever being pivoted to said first-named lever and disposed in operative relation to said switch and having an arm in contact with the handle.

10. In a blowpipe igniting apparatus, a movable electric contact member having a rounded end, an electric terminal, a spring holding said member out of contact with said terminal, and a lever constructed and arranged for sliding engagement with the rounded end of said member 45 for moving said member against the action of said spring into contact with said terminal. 50

11. For use in igniting a blowpipe, a gas control lever, a push switch carried by said lever, and a second lever pivoted to said gas control 55 lever for operating said switch.

12. An igniting circuit comprising a blowpipe having a handle, a push switch carried by the handle, said push switch having a rounded end on one member thereof, a lever carried by the 60 handle, and a roller journaled on one arm of said lever for rolling contact with the rounded end of said switch to operate said switch.
